UNITED STATES PATENT OFFICE.

WARREN R. TOWNSEND, OF GRAND RAPIDS, MICHIGAN, ASSIGNOR TO HIMSELF, AND CHARLES S. KNIGHT, OF SAME PLACE.

AUTOMATIC WASTE-VALVE FOR ENGINE-CYLINDERS.

SPECIFICATION forming part of Letters Patent No. 320,826, dated June 23, 1885.

Application filed December 18, 1884. (No model.)

To all whom it may concern:

Be it known that I, WARREN R. TOWNSEND, of Grand Rapids, in the county of Kent and State of Michigan, have invented a new and useful Improvement in Automatic Waste-Valves for Engine-Cylinders, of which the following is a full, clear, and exact description.

The object of my invention is to provide for escape of water from engine-cylinders without the loss of steam incident to the use of the ordinary cylinder-cock; and the invention consists in an automatic valve constructed to be closed by the steam-pressure and to open by a spring when the boiler-pressure is cut off from the cylinder, as hereinafter described and claimed.

Reference is to be had to the accompanying drawing, forming a part of this specification, which shows my improved valve in longitudinal section.

The body A of the valve is made with a neck, a, for the connection to the engine-cylinder and with an outlet, b, threaded for connection of a waste-pipe. The valve proper, c, is a disk upon a stem, d, that extends through the screw-cap e loosely. The stem is packed by a gland, h, and carries on its projecting end, between the gland and a nut, f, a spiral spring, g, that acts to move the stem outward and lift the valve from its seat. The valve c seats at h on the interior of the case above the outlet, and beneath the seat is a cross-bar guiding the valve-stem. Above the valve the

stem passes through a tube, i, that projects 35 from cap e, which tube serves as a guide and a shield to the stem.

In operation, the device being attached to the cylinder end in place of the usual cock, when steam is admitted to that end of the 40 cylinder it will close valve c to its seat and hold it there until the stroke of the piston is completed and the exhaust commences, when the spring g instantly opens valve c, and any water in the cylinder is forced out on the return-stroke of the piston. When the engine is at rest, the valve remains wide open, thereby allowing free escape of water.

It can be readily seen that, by the closing of the valve when the steam-pressure is on, 50 the waste of steam ordinarily occurring with cylinder-cocks is avoided, and that the device requires no attention, as it is always operative.

Having thus described my invention, I claim 55 as new and desire to secure by Letters Patent—

In a waste-valve, the combination, with the body A, provided with the inlet a and outlet b and the valve-stem d, of the cap e, provided with the tube i, projecting down into the body 60 and serving as a shield and guard to the valve-stem, substantially as herein shown and described.

WARREN R. TOWNSEND.
